Primary Examiner — Stella M Reid

Assistant Examiner — Elizabeth J Oswecki

(74) Attorney, Agent, or Firm — Gallagher & Dawsey Co.,
LPA; Michael J. Gallagher; David J. Dawsey(57) **CLAIM**

We claim the ornamental design for a bottle, as shown and described.

DESCRIPTION

FIG. 1 is a perspective view of a bottle showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan thereof; and,

FIG. 7 is a bottom plan view thereof.

The broken line disclosure represents non claimed subject matter and forms no part of the claimed design.

1 Claim, 4 Drawing Sheets# US D635,464 S
